UNITED STATES PATENT OFFICE.

CARL O. CARLSON, OF CAZENOVIA, WISCONSIN.

BARN-CLEANER.

1,243,257.

Specification of Letters Patent. Patented Oct. 16, 1917.

Application filed February 18, 1916. Serial No. 79,144.

To all whom it may concern:

Be it known that I, CARL O. CARLSON, a citizen of the United States, residing at Cazenovia, in the county of Richland and 5 State of Wisconsin, have invented certain new and useful Improvements in Barn-Cleaners, of which the following is a specification.

The present invention has relation to certain new and useful improvements in barn cleaners; and as its primary object contemplates the provision of a novel device of this nature that is to be operable in the drain or gutter of the barn, in order to collect the 10 manure and other foreign matter having been deposited therein, and which may be expeditiously handled by the operator in order to effect the dumping of the collected matter.

Another object of my invention is to provide a novel device of the nature aforesaid wherein means are provided to draw the manure or other foreign substance into the body of the cleaner and move the latter forwardly in the trough or gutter simultaneously, upon one stroke of the operating lever.

A further object of my invention is to provide a device of the above character which 30 may be suspended from a cable and elevated from the ground so that it may be quickly and easily conveyed to the desired dumping point.

A still further object is to provide means to normally retain the dispensing gate of the cleaner in a closed position, both during operation of the device in the gutter and the conveying of the same to the desired dumping point, and improved mechanism to become operable at a predetermined time to automatically open the dispensing gate and at the same time, effect the operation of conveyer means to cause the dispensement of the contents of the cleaner.

A yet further object of my invention is to provide a device of the nature aforesaid which consists of but a few simple parts, and which may be manufactured at a comparatively low cost.

Various other objects and advantages will become apparent during the continuance of the following description.

These objects are accomplished by such means as are shown in their preferred form 55 in the accompanying drawings, described in the following specification and then more

specifically pointed out in the appended claims.

In the accompanying drawings wherein like characters designate like parts throughout the several views:—

Figure 1 is a view in top plan, showing my invention as in its preferred embodiment;

Fig. 2 is a view in longitudinal section showing the parts as in their normal position;

Fig. 3 is a view showing the device suspended on a cable and the dispensing gate in an open position;

Fig. 4 is a view in rear elevation showing the device also suspended from the conveying cable;

Fig. 5 is a view showing the device as in a position prior to the dumping operation;

Fig. 6 is a view in detail of the mechanism for effectually supporting the rake structure which serves to draw the manure onto the shovel and hence to the conveyer means.

In reducing my invention to practice, I first provide a suitable body or container structure 10, which, by reason of the nature of the function ascribed thereto, is preferably constructed of sheet metal or other durable material. The body consists generally of a bottom portion 11, having spaced side members 12 associated therewith. The bottom 11 may be in turn provided with suitable supporting means which, in the present embodiment, consists of spaced carrying wheels 13 and 14 respectively; the latter being of course supported by the usual brackets 15. Any desired form of reinforcing means may be associated with the bottom 11 and as well as the side members 12, in order to render the same more durable; however, in view of the fact that this is but an arbitrary feature, it is pointed out that I am not limited to the specific means shown. In the present embodiment, reinforcing means consist of lateral strips 16 that are associated with the bottom 11 and similar strips 17 that are arranged on the side walls 12. This renders the device obviously more durable.

At their rear end, the side pieces 12 are connected through the instrumentality of a cross bar 18 to which is hingedly connected, as at 19, a dispensing gate 20; the latter being designed to normally lie in a closed position, such as clearly shown in Fig. 2. The gate 20 carries a slidably

- mounted retaining pawl 21, as at 22, the latter being designed to engage with a keeper 23 on the bottom 11, when the gate is in a closed position, in order to securely 5 retain the latter against accidental dislodgment. However, means are provided to automatically actuate the pawl 21 to release the said gate, such as will subsequently appear.
- 10 Within the body 10, I mount transverse carrying shafts 24 and 25 respectively, upon which are carried spaced rollers 26, and about the rollers are trained conveyer belts 27. The belts 27 are in turn connected by 15 transverse conveyer slats 28, thereby presenting an endless conveyer for receiving the material delivered into the body 10. In other words, the material entering the body 10 is deposited upon the conveyer so that 20 by movement of the conveyer during the dumping operation, all of the material may be quickly and easily removed from the body. This particular operation, however, will be described more clearly hereinafter.
- 25 I now provide a suitable shovel 29 that may be formed of sheet metal or the like, the same carrying suitably attached side pieces 30, which in turn have pivotal connection, as at 31, to the side pieces 12 of the body 10. The shovel is preferably attached to the body 10 at a point whereby the inner edge thereof will be slightly above the conveyer mechanism, in order that the material delivered to the body will be deposited on 30 the conveyer. Consequently, by pivoting the shovel in the manner shown, the front edge will normally contact with the surface or bottom of the gutter or other structure, with which the device is engaged, while the 35 rear edge will be positioned at the desired point. This will necessitate the shovel lying in a slightly inclined position. However, by action of the rake mechanism subsequently described, it will be seen that the 40 manure and other foreign material will be quickly and easily drawn into the shovel and hence fed to the conveyer mechanism. The shovel shown in the present embodiment may be formed from a single section 45 of material, the side pieces 30, being bent upwardly at right angles to the body. This particular arrangement, however, is arbitrary and it is to be understood that I do not limit myself to the specific form shown.
- 50 I now provide the body 10 with a transverse carrying bar 32 upon which is mounted a suitable operating arm or lever 33, the same being preferably fixed to the bar by any desired means. The operating arm or 55 lever is oscillatable longitudinally with respect to the body 10 and is designed to control operation of both the means to draw the manure or other foreign material into the body of the device and the means to move 60 the cleaning device forwardly into the
- trough or gutter; both operations being simultaneous. The operating arm or lever may be constructed of any desired material; however, it is pointed out that an ordinary wooden handle would suffice under certain 65 conditions.
- 70 The shovel 29 carries an arcuately curved trip member 34 which, in the present embodiment, has certain portions 35 journaled through the side pieces 30 of the shovel, with its extreme end portions 36 forming abutment lugs to coact with the edges of the side pieces, such as will subsequently appear. Intermediate its ends, the trip member is formed into a stirrup 37, which is 75 designed to receive a shank of the rake mechanism, presently described. Suitable retractile springs 38 are each connected at one end with one of the end portions 36 of the trip member, while the other ends of 80 said opening have connection with the pivot members 31, above referred to. Therefore, by action of the springs 38, the trip member 34 will have a normal tendency to move forward and upward with respect to 85 the shovel. However, by reason of the weight of the rake, such movement is prevented except at times during operation of the rake as hereinafter described.
- 90 The rake structure that operates in conjunction with the shovel 29 consists generally of a body 39 which carries suitably spaced lateral bars 40 having depending rake teeth 41. At its rear end, the body 39 carries a shank 42 that operates the stirrup 95 37 of the trip member, the rear end of the shank being formed into a bearing 43 to embrace the operating arm or lever 33, as clearly shown in Figs. 2 and 3. The shank 42 is in turn provided with a receiving recess or bearing 44 which accommodates the rung 37' of the stirrup 37 at certain times, causing the trip member to move with the 100 rake structure, a certain distance, such as will be subsequently described. In other 105 words, upon movement of the operating arm or lever 33 to the position shown in Figs. 2 and 3, the shank 42 of the rake structure will be drawn rearwardly so that the recess 44 thereof receives the rung of the stirrup 110 37, which latter is pressed into said recess by action of the spring 38 on the element 36. Consequently, upon forward movement 115 of the operating arm or lever and consequent movement of the rake structure, the trip 120 member will also be rocked so as to elevate the rake structure, in an obvious manner. Upon continued movement in this direction, the ends 36 of the trip member 34 will be 125 subsequently engaged with the sides 30 of the shovel, thereby preventing further movement of the member 34 and causing disengagement of the stirrup 37 and the recess 44. Upon the disengaging operation as aforesaid, the trip member will again fall 130

into the position shown in Figs. 2 and 3, by the weight of the rake structure thereon and will be engaged with the manure or other foreign matter adjacent the shovel. Consequently, upon drawing the operating lever rearwardly again, the rake will serve to draw the manure or other foreign material onto the shovel 29. Upon releasing of the rake structure after its movement to a forward position, the same will fall by action of its own weight and thereby drive the teeth 41 onto the manure or other foreign material. The springs 38 having a normal tendency to move the trip member forwardly, will of course insure efficient co-operation or coaction between the stirrup 37 and the recess 44 as is obvious.

The operating arm or lever 33 is further provided with a fixed bearing or eyelet 45 to which connects one end of the rearwardly directed rod 46. Adjacent its rear end, the rod 46 is bent at the point 47 in order to form a depending leg 48 to extend at substantially right angles to the forward end 25 of the rod 46. The cross bar 18 is provided with a recess 49 to form a way or bearing for the rod 46, while a pivoted keeper 50 is associated with the bar 48 to normally overlie the rod 46, as shown in Fig. 2, and retain the same against upward movement. When in the position shown in Fig. 2, the rod or keeper 50 will be held against vertical movement by a catch 51. This construction is more clearly shown in Fig. 1, 35 wherein the keeper 50 is shown in a locked position, it being held in place by the catch 51. Although the rod 46 is normally held against vertical movement, movement of the same longitudinally with respect to the body 40 10 by means of the operating arm or lever 33 is of course permitted.

Adjacent its rear end the rod 46 carries a fixed collar 52 from which depends a flexible element 53 having connection at its lower 45 end with the retaining pawl 21 of the dispensing gate as at 54. Consequently, upon upward movement of the rod 46, the retaining pawl 21 will be withdrawn from engagement with the keeper 23. The bent portion 50 48 of the rod 46 also carries adjacent its lower end, a pair of pivoted arms 55 and 56, and as at 57, while coil springs 58 are employed to normally retain said arms in the position shown in Fig. 1. When in this 55 position, the arms project slightly beyond the sides 12 of the body and are suitably curved as at 59 to engage with the side of the gutter or way in which the device is being operated. In other words, when in engagement with the side walls of the gutter or way, the arms will permit of forward movement of the device, since they may move rearwardly upon their pivot points, but will effectually prevent rearward movement. Therefore, upon oscillation of the

operating arm or lever, the arms 55 and 56 will be made to move the device forwardly in the way or gutter, as is obvious.

In order to couple the operating arm or lever 33 and the rod 46 after the body 10 has become full and it is desired to be dumped, I provide the said operating arm with a depending hook 60. The hook is normally suspended above the rod 46, but when desired, the operating arm or lever 75 may be moved downwardly into the position shown in Fig. 3, whereby the hook may be engaged with the rod as shown. Therefore, when the operating lever is coupled with the rod, the said rod will be oscillated with the operating lever, after being released by the keeper 50. The oscillating rod or lever also carries an eyelet 61 for engagement with a suitable hook 62, prior to the dumping operation.

The operation of my invention prior to the dumping operation, is substantially as follows:

Normally, the parts are in the position shown in Fig. 2, the gate 20 being in a closed position and held in place through the instrumentality of the pawl 21, and the rod 46 being held against upward movement by the keeper 50. The device being disposed in the gutter or way, the arms 55 and 56 90 will be engaged with the sides of the gutter or way in the manner aforesaid. Upon movement of the operating lever forwardly, the rake structure will be elevated and released by the trip member 34 as aforesaid, 95 while the rod 46 will draw the arms 55 and 56 forwardly in the way and finally hold the same in juxtaposed relation to the gate 20. Therefore, upon rearward movement of the operating lever, the arms 55 and 56 will 100 lock with respect to the gutter or way so that the body 10 will be thrust forwardly in the gutter, while the rake structure will be drawn rearwardly so as to feed the manure or other foreign material onto the shovel 110 29. Consequently, as the oscillation of the operating lever is continued, the device will be moved forwardly in the gutter, while the manure and other foreign material will be continually drawn onto the shovel and subsequently forced to the conveyer mechanism.

After the body 10 has become filled and the operator desires to dump the same, suitable mechanism is employed in order to move and handle the device in a most expeditious manner. This mechanism consists generally of a yoke 63, having guide wheels 64 to operate on the cable 65, and of a depending arm 66, as clearly shown in Fig. 3. At its lower end, the arm 66 is bifurcated as at 67, through which bifurcated portion is journaled a windlass 68. The windlass 68 is operable by means of the handle portion 69 and is designed to receive one end of a cable 70, whose other end is connected with 120

the hook 62 as shown in Fig. 3. Consequently, upon winding of the cable 70 on the windlass the entire cleaning device will be withdrawn from the gutter or other way within which it is being operated. The arm 66 further carries a diagonally depending finger 71 as at 72, the latter also having its free end bifurcated as at 73, whereby it may effectually limit movement of the operating arm or lever 33, at certain times, (see Fig. 5).

I further provide the gate 20 with inwardly directed conveyer operating arms 74, which, in the present embodiment are formed of a single strand of heavy durable wire. The intermediate portion of the said strand of wire is subsequently bent to provide a portion 75 to lie between the conveyer slats 28 so that upon opening movement of the gate, the conveyer mechanism will be operated so as to empty the contents of the body 10. When in its normal position, the portion 75 of the arm 74 lies adjacent the forward end of the conveyer, as shown in Fig. 2.

Therefore, when desiring to empty the contents of the cleaner the hook 62 is engaged with the eyelet 61 of the operating arm or lever, as shown in Fig. 3, the hook 60 of the operating lever being in turn engaged with the rod 46 in the manner shown. The handle 69 of the windlass is then operated so as to wind the cable 70 thereon and thus raise the entire cleaning structure from the gutter or other way in which it is being operated, while the operator may move the arm 66 so as to cause the entire structure to move on the cable 65 to the desired point. Adjacent the point of dumping, the cable 65 carries a depending rod 76 whose lower and free end portion is designed to engage with the end of the keeper 50, while the upper end of the said arm designated by the numeral 77, serves as a stop for the carrying wheels 64. Consequently, when the structure reaches the point of dumping, the rod 76 will be engaged with the keeper 50 so as to disengage the latter from the catch 51, whereupon the weight of the cleaning structure will cause the rocking of the operating arm or lever as well as the rod 46, to cause the opening of the gate 20 and the simultaneous actuation of the conveyer mechanism by the arms 74 and the portion 75 thereof. In other words, the releasing of the rod 46 causes the rocking of the lever 33 by action of the weight of the device, so as to cause the releasing of the pawl 21 and the opening of the gate 20 to the position shown in Fig. 3; while the arms 74 are drawn rearwardly so as to effect the operation of the conveyer mechanism to empty the contents of the body 10.

From the foregoing, it will be recognized that I have provided an improved barn

cleaner which is readily operable in the drainage trough so as to clean the same and convey the manure or other foreign material to the point of dumping. It will also be recognized that the entire cleaning structure may be easily and quickly conveyed to the point of dumping and automatically emptied when desired. In view of the fact, therefore, that the advantages and novel features of the invention appear to be apparent, it is believed that further detail description is deemed unnecessary.

In reducing my invention to practice, I find that the form referred to herein as the most practical and preferred embodiment is the most efficient, but realizing that certain conditions will necessarily vary in concurrence with the adoption of my device, I desire to emphasize the fact that various minor changes in the details of construction and in the proportion of parts may be resorted to when required without sacrificing any of the advantages of my invention as defined in the appended claims.

Having thus fully described my invention, what I claim as new and desire to secure by Letters Patent is:—

1. In a cleaning device, the combination of a body portion, means to feed the material into said body portion, means to move said body portion step-by-step in one direction, and a universal member to operate the feeding means and the step-by-step propelling means and to coöperate with a support for effecting the raising of the device.

2. In a cleaning device, the combination of a body structure, a conveyer in said body structure, a shovel secured to the front portion of said body structure, means coöperative with said shovel to feed extraneous material onto said conveyer, means for moving said body structure step-by-step in one direction, an outlet gate, means automatically operable to move said conveyer to empty the contents of said body structure through said outlet gate, and universal operating means for operating the second and third said means.

3. In a cleaning device of the character described, the combination of a body structure, means to movably support said body structure, a conveyer in said body structure, a shovel arranged at one end of said body structure, means coöperating with said shovel to feed the material to said conveyer, a dispensing gate, means operable by said dispensing gate to move said conveyer to empty the contents of said body structure, and universal means for operating the second and third said means as and for the purpose specified.

4. In a cleaning device of the character described, the combination of a body structure, means to movably support said body structure, conveyer mechanism in said body

- structure, a shovel arranged at one end of said body structure for taking up extraneous material, means to draw the material from said shovel into said body structure, means operable to move said body structure step by step in one direction, operating means common to the first and second said means and operable to effect simultaneous raking and step-by-step feeding thereby, an outlet gate 5 operable by said operating means, and means to automatically actuate said conveyer mechanism upon the opening of said outlet gate to empty the contents of said body structure, as and for the purpose specified.
5. In a device of the character described, a rake, means to move said rake longitudinally, and means supported independently of said rake and operable thereby to elevate and drop said rake.
6. In a device of the character described, the combination of a body structure, means to movably support said body structure, a shovel at one end of said body structure, an outlet gate at the other end of said body structure, means to draw the material into said body structure, means controllable by said gate to empty the contents of said body structure, and universal manipulative reciprocatory means for operating the first and second said means, as and for the purpose specified.
7. In a device of the character described, the combination of a container, an outlet gate for said container, means to operate said outlet gate, and means automatically operable upon the opening of said gate to force the contents of said container through said gate.
8. The combination of a container, a gate provided for said container, means to unlock said gate and open said gate, and means controllable by the opening of said gate for forcing the contents of the container through said gate.
9. The combination of a container, an outlet gate provided for said container, means to open said outlet gate, and means operable by said gate to force the contents of said container through said gate.
10. In a device of the character described, a body structure, means to movably support said body structure, a shovel arranged at one end of said body structure, a trip member pivotally associated with said shovel, means to limit the movement of said trip member, a rake structure to draw the material into said shovel, a shank on said rake structure coöperating with said trip member, an actuating lever to move said rake structure, and said shank provided with a recess to receive a portion of said trip member at certain times, as and for the purpose specified.
11. In a device of the character described, a body structure, means to movably support said body structure, a shovel carried by said body structure, an arcuately curved trip member pivotally associated with said shovel, means to limit the amplitude of movement of said trip member, means having a tendency to retain said trip member in a normal position, a rake structure, a shank on said rake structure coöperating with said trip member, an actuating lever to move said rake structure longitudinally with respect to said body structure to draw the material onto said shovel, said shank provided with a recess to receive a portion of said trip member at certain times, whereby said trip member may be moved, together with said rake structure, and means to move said body structure in one direction simultaneously with the operation of said operating lever, as and for the purpose specified.
12. In a device of the character described, a body structure, means to movably support said body structure, a shovel carried by said body structure, a strand of wire having its intermediate portion arcuately curved, portions of said strand of wire journaled through portions of said shovel, the ends of said strand of wire being bent to form abutments to limit the amplitude of movement of said intermediate portion, a stirrup formed from the intermediate portion of said wire, a rake structure coöperating with said shovel and having a shank operating in said stirrup, a lever to actuate said rake structure, said shank provided with a recess to receive a portion of said stirrup at certain times, and means to move said body structure in one direction, simultaneously with the actuation of said lever, as and for the purpose specified.
13. In a device of the character described, the combination of a body structure, means to movably support said body structure, conveyer mechanism in said body structure, means to draw extraneous material into said body structure, an outlet gate for said body structure, universal means for controlling the second said means and for opening said gate and means operable by the opening movement of said outlet gate to empty the contents of said body structure, as and for the purpose specified.
14. In a device of the character described, the combination of a body structure, means to movably support said body structure, conveyer mechanism in said body structure, means to draw extraneous material into said body structure, an outlet gate for said body structure, means coöperative with the second said means for controlling opening of said gate, means controllable by said outlet gate to actuate said conveyer mechanism upon opening movement of said outlet gate to empty the contents of said body structure, as and for the purpose specified.

and means automatically operable to move said body structure in one direction, as and for the purpose specified.

15. In a device of the character described, 5 a body structure, means to movably support said body structure, an operating lever, means operable by said operating lever to draw extraneous material into said body structure, means controllable by said operating member to move said body structure in one direction, an outlet gate associated with said body structure and controllable by said operating member for effecting the opening of the gate, and means controllable 15 by said outlet gate to force the contents of said body structure through the opened gate, as and for the purpose specified.

16. In a device of the character described, 20 a body structure, means to movably support said body structure, means at one end of said body structure to draw the material acted upon thereinto, means arranged adjacent the other end of said body structure to move said body structure in one direction, means to raise and lower said body structure, and means to automatically empty 25 said body structure, as and for the purpose specified.

17. In a device of the character described, 30 a body structure, means to movably support said body structure, means to draw the material acted upon into said body structure, an outlet gate for said body structure, means to move said body structure in one direction, means to raise and lower said body structure, and means to automatically empty said body structure, as and for the purpose specified.

ture, means to move said body structure in one direction, means to raise and lower 35 said body structure, and means to automatically open said outlet gate at certain times to cause the emptying of the contents of said body structure, as and for the purpose specified.

18. In a device of the character described, the combination of a body structure, means to movably support said body structure, conveyer mechanism in said body structure, a shovel arranged at one end of said body structure, means coöperating with said shovel to draw extraneous material into said body structure, an outlet gate for said body structure, means to move said body structure in one direction, universal means 40 for controlling the second and third said means, raising means coöperative with said universal means so as to raise and lower said body structure, means cooperative with the raising means so as to cause the automatic opening of said gate at certain times, and means controllable by said gate to actuate said conveyer mechanism and thereby cause the emptying of said body portion, as and for the purpose specified.

In testimony whereof I affix my signature in presence of two witnesses.
